UNITED STATES PATENT OFFICE

2,564,998

AIR CONDITIONING DEVICE

Thomas E. Sayers, Minneapolis, Minn.

Application August 14, 1948, Serial No. 44,336

1 Claim. (Cl. 62—133)

1

This invention has relation to an air conditioning device.

An object of the invention is to provide an air conditioning device which will be of new and improved construction.

A further object is to provide an air conditioning device devised to be especially useful for the purpose of employment within the interior space of automotive vehicles and incorporating desirable and improved features and characteristics.

And a further object is to provide an air conditioning device of construction and operative in the manner as hereinafter set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claim which follows.

In the accompanying drawing forming a part of this specification,

Fig. 1 is a side elevational view of an air conditioning device made according to the invention;

Fig. 2 is a top plan view of the air conditioning device;

Fig. 3 is a central longitudinal sectional view, taken on line 3—3 in Fig. 2; and

Fig. 4 is a central longitudinal sectional view, taken on line 4—4 in Fig. 1.

A housing 10 of the air conditioning device is of curvilinear configuration in the disclosure as made.

A partition 11 within and across the housing 10 provides a relatively small, first chamber 12 within said housing at one side of said partition and a comparatively large, second chamber 13 within the housing at the side of the partition opposite the first chamber 12. Said partition 11 is cut away at one side thereof to provide a communicating passageway 14 between said first and second chambers 12 and 13. The communicating passageway 14 is contiguous with a wall of the housing 10, and the partition 11 separates and isolates the first and second chambers 12 and 13 from each other save by way of said communicating passageway 14.

An electric motor 15, within the first chamber 12 and suitably and conveniently supported, as at 16, upon the partition 11, is adapted to be energized by electrical energy from any suitable

2

source (not shown), and a blower 17 fixed upon the shaft of the electric motor 15 is for forcing air out of said first chamber 12, through the communicating passageway 14 into the second chamber 13 and out of said second chamber. The electric motor 15 and the blower 17 are in spaced relation to said communicating passageway 14, and the construction and arrangement are such that said blower forces air toward said communicating passageway.

The housing 10 includes an openable door 18, contiguous with the first chamber 12 and at the side of the electric motor and blower opposite the communicating passageway 14, for affording access to said electric motor and blower, and air inlet passageways through said door to said first chamber 12 are denoted 19. Said first chamber 12 is closed save for said openings 19 and communicating passageway 14.

20 The second chamber 13 contains a rectilinear support 20 for a slidable drawer 21 adapted to receive a cooling medium, such, for example, as Dry Ice or ordinary ice. The rectilinear support 20 may be assembled with the housing 10 in any suitable and convenient manner. As disclosed, said rectilinear support is constituted as a bottom wall 22, an interior end wall 23 extending upwardly from said bottom wall and spaced apart, parallel side walls 24, 24, and the rectilinear support is open at its upper side and exterior end. The bottom wall 22 of said rectilinear support slants downwardly from its exterior portion to an intermediate part of said bottom wall and opens to a drain pipe 25 leading from the bottom wall, and the open, exterior end of the rectilinear support 20 is contiguous with an opening through a wall of the housing 10 situated at a side of said housing opposite and below the openable door 18. The drain pipe 25 leads to a bottom wall of the housing 10 by way of a transverse wall 26, and said bottom wall normally is closed by a spring pressed plug 27.

45 The slidable drawer 21 rests upon the bottom wall 22 of the rectilinear support 20 and spans the distance between the side walls 24, 24 to be slideable inwardly and outwardly of the housing 10 and said rectilinear support. Said drawer 21 includes a base wall 28 having perforations 29, an interior end wall 30 extending upwardly from said base wall, an exterior end wall 31 extending upwardly from the base wall, and spaced apart, parallel side walls 32, 32 connecting the interior and exterior end walls 30 and 31. The perforations 29 are for passage of water to the drain pipe 25 when ordinary ice is the cooling medium em-

ployed. The slidable drawer 21 is open at its upper side, and the construction and arrangement will be such that the second chamber 13 will be closed at the location of the open, exterior end of the rectilinear support 20 and the exterior end wall 31 of the slidable drawer 21 when said slid- 10 able drawer is in its closed position as in Fig. 3 of the drawing. Stated differently, said exterior end wall 31 includes extension portions at its upper, lower and opposite sides adapted to seal the second chamber 13 closed when the slidable drawer 21 is in shut condition.

The slidable drawer 21 is in somewhat spaced relation to the partition 11, and in parallel relation to said partition in the disclosure as made. 15 The interior end walls and spaced apart side walls of the rectilinear support and slidable drawer are in spaced relation to the bounding side walls of the housing 10, and the bottom wall 22 of said rectilinear support is in spaced relation to the transverse wall 26 of said housing. Upper extension portions 33, 33 upon the spaced apart side walls 24, 24 of the rectilinear support 20 are contiguous with the adjacent surface of the partition 11 and with opposite side walls of the housing 10, and lower extension portions 34, 34 upon said spaced apart side walls 24, 24 are contiguous with the adjacent surface of said transverse wall 26 and also with opposite side walls of said housing. Thus is provided an air channelway from the 30 communicating passageway 14 extending over the top of the slidable drawer 21, along the inner side of the interior end wall 23 of the rectilinear support 20 and under the bottom wall of said rectilinear support, said air channelway being bounded at its upper portion by said partition 11, at its lower portion by the transverse wall 26, at 35 its opposite sides by the upper and lower extension portions 33, 33 and 34, 34, and at its intermediate portion by a wall of the housing 10 adjacent the interior end wall 23. The communicating passageway 14 is entirely within the confines of the air channelway, and outlet passageways from said air channelway through a wall of the housing 10 and within the confines of said air channelway, are denoted 35. Said outlet passageways 35 are at the side of the slidable drawer 21 opposite the communicating passageway 14, directly beneath said communicating passageway, in the disclosure as made.

A curvilinear deflector 36 in the air channelway beneath the communicating passageway 14 is for directing air traveling from the first chamber 12 into the inlet end of the air channelway to pass along the part of said air channelway over and contiguous with cooling medium in the slidable drawer 21 to the intermediate portion of the air channelway.

A bracket 37 is for supporting the air conditioning device upon a structure, such, for example, as the dash of an automotive vehicle, and a hand piece 38 upon the exterior end wall 31 of the slidable drawer 21 is for ready manipulation of said slidable drawer.

The manner in which the air conditioning device functions will be apparent. When the blower 17 is in operation, air will be drawn into the first chamber 12 by way of the air inlet passageways 19 through the openable door 18, and the drawn in air will be forced out of said first chamber 12 through the communicating passage-

way 14 and made to travel along the air channelway, first over the open, upper side of cooling medium in the slidable drawer 21, then along the inner side of the rectilinear support 20, and finally along and under the bottom wall 22 of said rectilinear support. The forced air will pass out of said air channelway and out of the housing 10 through the outlet passageways 35. It will be apparent that air forced through the air channelway will travel along the upper, interior and lower sides of the cooling medium thus to be capable of giving up its heat to the maximum extent possible.

When cooling medium in the slidable drawer 21 becomes spent, said slidable drawer can be removed, replenished with cooling medium and replaced.

What is claimed is:

A portable air conditioning device comprising a housing, first and second horizontal partitions within and across said housing providing therewith a first chamber above said first partition, a second chamber below said first partition and above said second partition and a third chamber below said second partition, said first chamber being open to atmosphere by way of an inlet to said housing and there being a communicating opening in said first partition between the first and second chambers adjacent the wall of the housing opposite said inlet, said first chamber being closed save for said inlet and communicating opening, a container in said second chamber spaced from said first and second partitions, a drawer for ice slidably supported by said container accessible at an outer side of said housing and having a perforated lower wall, said housing, first partition and container providing an air channelway contiguous with said communicating opening and extending across the top, one of the sides and the bottom of said container, said air channelway being closed when said drawer is in inserted position save for said communicating opening, and an outlet from a lower portion of the air channelway below said container, a funnel shape drain constituted at the bottom wall of said container, a drain pipe leading from said funnel shape drain to a point inside said third chamber, said housing being provided with a drain hole at a lower portion of said third chamber, a drain plug normally closing said drain hole accessible from an outer side of said housing and adapted to be manually actuated to open position with respect to said drain hole, a blower for forcing air through said channelway mounted on said first horizontal partition in said first chamber, and an external supporting bracket integral with said housing for securing said device to a wall.
